UNITED STATES PATENT OFFICE.

EDWARD B. ALLEN, OF PORTLAND, MAINE, ASSIGNOR TO JAMES W. BROOKS, OF CAMBRIDGE, MASSACHUSETTS, TRUSTEE.

HEEL-NAILING MACHINE FOR BOOTS OR SHOES.

SPECIFICATION forming part of Letters Patent No. 310,488, dated January 6, 1885.

Application filed May 3, 1884. (No model.)

To all whom it may concern:

Be it known that I, EDWARD B. ALLEN, residing in Portland, in the county of Cumberland, State of Maine, have invented certain new and useful Improvements in Heel-Nailing Machines for Boots and Shoes, whereof the following description, with the accompanying drawings, is a specification, like letters indicating like parts.

10 The invention herein to be described is intended as an improvement upon the machine represented in United States Patent No. 203,440, granted to C. W. Glidden, or upon what is known in the market as the "McKay & Bigelow Heeling-Machine." In that machine the top lift to complete the nailed heel is presented to or laid upon the upper side of the usual pivoted top-lift plate by hand, and so, also, the top-lift plate, located next the top 15 of and resting directly on the nail-box to support the top lift, and which, when the top lift is being applied, is turned into position to cover the nail-holes in the said nail-block, is moved by hand. Operating the top-lift plate 20 by hand and then placing said top lift thereon by hand prevents the rapid operation of the said machine, and it is necessary to run it at a very much slower speed than that at which it might be practically run.

25 30 One special feature of my invention is to provide mechanism whereby the top-lift plate may automatically be turned quickly into position after the body of each heel has been nailed upon the boot or shoe.

35 Another feature of my invention is to provide a mechanism whereby the top lift may be automatically presented in correct or central position upon the top-lift plate, in order that the top lift may be correctly attached to 40 the protruding ends of the nails of the heel. I have also provided a hook or latch to prevent rebound of the die-bed spindle.

45 Figure 1 is a partial left-hand side view of a heel-nailing machine of usual construction, with my improvements attached. Fig. 1^a is a sectional detail taken in the line $x-x'$, Fig. 1, looking down. Fig. 2, on a smaller scale, represents by dotted lines the upper portion of the right-hand side of a heel-nailing machine, 50 my improved top-plate-moving mechanism

being added thereto in full lines; Fig. 3, an enlarged detail of the latch which holds the actuating slide-rod of the top-lift carrier; Fig. 4, an enlarged detail of the device which trips the latch; Fig. 5, details of the rod-carrying latch. Fig. 6 shows the latch mounted on the slide-rod of the top-lift carrier, and the spring for moving the said rod-carrying latch. Fig. 7 is a top or plan view of the top-lift carrier, shown as holding a top lift between its 60 jaws; Figs. 8, 9, and 10, details of some of the devices shown in Fig. 7. Fig. 11 is a detail of the actuating slide-rod referred to in connection with the spring which carries it forward; Fig. 12, a section of Fig. 11 in the line $x'-x'$; 65 Figs. 13 to 15, inclusive, enlarged details of the devices located between the usual toggle mechanism of the said patented machine and the rod which actuates the top-lift plate. Figs. 16 and 17 show details of mechanism to 70 prevent the rebound of the die-bed spindle; Fig. 18, a detail in side view of the devices for moving the top-lift plate automatically; Fig. 19, a detail of the actuating slide-rod for the top-lift carrier.

75 The frame-work A A', sprocket or chain wheels M N, chain C, chain-moving carriage K, lever K' to move it, the track C², on which the carriage is moved, the toggle-joint connection T T, lever T², nail-box E, and die-bed 80 spindle W, are all substantially as in the said patent, so need not be here further specifically described.

To automatically present the top lift, L, between the top-lift plate R, pivoted at R² at 85 the top of the usual nail-box, E, and the end of the heel attached to the shoe carried by the usual jack, (the said heel having the heads of the nails protruding therefrom, as usual, to have the top lift impaled on them at the next 90 ascent of the die-bed spindle W,) I have provided a top-lift carrier composed, as herein shown, of pivoted or yielding jaws o o, carried by levers or arms n n, mounted on a head having connected with it means to move the said 95 carrier horizontally. The jaws are pivoted upon the levers or arms n at k³, and the said levers are pivoted at m on the head j, springs g acting to keep the jaws pressed toward the top lift. The jaw m³ on the rod o² acts 100

against the curved end of the top lift. The head *j* is connected with a slide-block, *f*, by means of a dovetail projection, *i*, on one entering a correspondingly-shaped groove on the other, screws *k* holding the same in adjusted position. The block *f* is adjustably attached to a projecting arm, *d*, of the slide-rod *a*, placed in suitable bearings, *b* and *c*, fixed with relation to the frame-work A A', the bearings *b* being shown as forming part of a plate, *b*', attached to the frame A.

To prevent rotation of the slide-rod *a* in its bearings, the said rod is shown as made square from its shoulder B forward, and the bearing *c* has an opening of corresponding shape in cross-section; but, instead, the slide-bar may be round and be provided with a groove to co-operate with a spline, the said spline and groove preventing the rotation of the said rod. The slide-rod has attached to it by suitable screws the collars *d*', *z*', *v*, and *u*. Between the collars *v* and *u* the slide-rod is surrounded loosely by the rod-carrying latch *Q*, (see Figs. 1 and 5,) having at its lower end a toe, *t*, the upper end of the said latch being acted upon by one end of a spring, *y*, coiled about the rod *a*, and connected at its other end with the bearing *b*, the said spring acting to keep the lower part of the said latch against a latch-operating device composed of a bar, *P*, mounted on brackets *H*, the inner edge of the said bar being inclined, as shown in Fig. 1', with relation to the frame-work A A', and consequently with relation to the slide-rod *a*, which is parallel with relation to the frame-work. The slide-rod *a* is surrounded loosely by a collar, *c*', joined to the bearing *b* by links *a*', and between the collar *d*', fast to the said slide-rod, and the stationary yet loose collar *c*', referred to, the slide-rod is surrounded by a spiral spring, *e*', the normal tendency of which is to move the slide-rod *a* and its attached top-lift carrier from its full-line position, Fig. 1, into its dotted-line position, the carrier at such movement taking a top lift, *L*, from above the shelf *S*, attached to the frame-work A'. The slide-rod *a* has a notch, *D*, which, when the said slide-rod is in its farthest position to the left, (see Fig. 1,) as in full lines, is engaged by the rod-releasing lever or catch *f*', pivoted at *a*' on a lug, *g*', near the bearing *b*, the said lever *f*' being kept pressed toward the rod by a spring, *h*'. When the rod is so held back, the spring *e*' is compressed between the collar *c*' (the position of which is fixed) and the collar *d*'; and if the lever or catch *f*' is moved to release it from the said rod, the spring *e*' will immediately throw the rod *a* forward into its dotted-line position, thus enabling the carrier to place a top lift in position to be secured to the heel.

To turn the rod-releasing lever or catch *f*' at the proper time and release the rod *a*, I have connected with the lower member, *T*, of the usual toggle-lever, that turns the beam or lever *T*', a tripping device composed of a bar, *i*', pivoted at *k*', and sliding in a guide, *l*', the said

bar having a dog, *j*', pivoted upon it at *t*', the said dog having a hole which is entered by a spring, *W*', (see Fig. 4,) the said spring normally keeping the said dog in the position shown in Fig. 4, with its acting end extended beyond the bar *i*', so as to strike the lever or catch *f*' as the said bar is moved in the direction of the arrow thereon, Figs. 1 and 4, and turn the said lever or catch to release the rod *a*. The lever or catch having been moved to release the rod *a* and throw the collars *d*' *v* *u* and the rod-carrying latch and the top-lift carrier into their dotted-line positions, the said carrier must be withdrawn away from the top-lift plate and nail-box to permit the usual heel-trimmer to operate. The heel-trimming mechanism, of usual construction, derives its movement from the chain *C* over the sprocket-wheels or chain pulleys *M* *N*, and the chain is moved by the vibrating lever *K*', connected by a slot and pin with the carriage *K*, grooved to slide or ride on the track *C*'. As this chain is started in the direction of the arrow thereon to trim the heel, as usual, the toe *t* of the rod-carrying latch *Q*, acted upon at its upper end by the spring *y*, is caught by the carriage and carried along in unison with the same, and the said latch, held on the rod *a* between the two collars *v* and *u*, acts to move the rod backward and the carrier away from the top-lift plate; but as soon as the said latch has been moved back far enough to compress the spring *e*' and carry the notch *D* in the rod *a* opposite the lever or catch *f*', then the latter will immediately snap into the said notch and hold the rod until it is again released. As the carriage moves the latch *Q* backward or toward the rear of the machine, as described, the latch is made to travel at first near the inclined edge of the bar *P*, and is finally brought against the said edge, and by the time the lever or catch *f*' has engaged the notch the latch *Q* is moved so far about the rod *a* as a center by the bar *P* as to remove the toe *t* from engagement with the carriage *K*. As the bar *i*' is moved backward the dog *j*', as it strikes the latch *f*', turns on its pivot *t*', the spring *W*' yielding, and the latch *f*' is not moved out away from the rod *a*. The pin *t*' acts as a stop for the dog as the bar *i*' is moved forward or in the direction of the arrow. The rod *a* having been caught by the lever or catch *f*', the chain is thereafter reversed to return the usual trimming mechanism into its normal position. The acting faces of the jaws *o* and *m*' are serrated. The springs *q* and *r* act to keep the jaws pressed in the proper direction to hold the top lift. The devices shown in dotted lines, Fig. 2, to hold the shoe, are or may be all as usual in United States Patent No. 203,440, or as in the said McKay & Bigelow heeling-machine, and the said devices will operate all as usual.

Referring to Figs. 2 and 18, I will now describe one practical manner of operating the top-lift plate automatically. The top-lift plate *R*, pivoted, as usual, on the top of the nail-box *E* at *R*', has a laterally-extended arm,

R^3 , provided with a pin or projection, 12, which is engaged by a rod, z' , held in a yielding manner in the end of the part x' of a connecting-rod, $q' x' z'$, for automatically actuating the top-lift plate R. The part q' of the said connecting-rod has a collar, r' , provided with a pin, which is connected by link p' with a lever, p^2 , pivoted at p^3 , the said lever being in turn connected by a link, p^4 , with the pin 10 C ^{3} , which forms the junction of the two parts of the toggle T, and as the toggle is operated in usual manner the rod q' is moved backward and forward in the bearings or guides V' and W ^{2} . At its forward end the part q' of the connecting-rod has a vertical hole that receives a pin, 13, at the rear end of the part x' of the said rod, the said pin and hole permitting the part x' to rise and fall independently of the part q' without destroying their connection. The end of the part x' is provided with a disk-like end, 14, (see Fig. 18,) open at its center, and for a distance back from the said end the said part x' is slotted to receive one end of the part z' , the latter having fastened 25 to it two collars, 15 16, and being provided with two cushion-springs, 17 18, one at each side the disk 14, whereby the part z' is free to yield to a certain extent as the connecting-rod is reciprocated. Movement of the connecting- 30 rod described forward toward the operator causes the top-lift plate R to be turned aside off the nail-block E, in order that the die-bed spindle W, as it is next lifted, will, through usual devices actuated by it, drive nails into the heel to attach it to the sole, leaving the 35 heads of the nails protruding, to have the top lift, L, impaled thereon, as usual; and the nails having been driven into the heel, the backward movement of the top-lift-plate moving or connecting rod, q' , described effects the turning of the top-lift plate into position above, and to cover the nail-holes in the nail-box E preparatory to placing the top lift in position above it for the second rise of the 40 die-bed spindle W, as usual, to attach the top lift and trim the edge of the heel. The top-lift plate and the top-lift carrier are automatically operated in the same time as relates the one to the other, and with such relation 45 to the movements of the toggle and die-bed spindle and trimming mechanism as to cause the top-lift plate to cover the nail-box before the top lift is brought into position above the nail-box, the top-lift carrier placing a top lift 50 between the top-lift plate and the lower end of the attached heel as or just before the die-bed spindle is moved to effect the securing of the top lift to the heel. As the toggle is bent its joint C ^{3} is moved toward the front of the machine, the 55 rod q' is operated to turn the top-lift plate into position to cover the nail-box, and simultaneous therewith the top-lift carrier is operated to place a top lift between the said plate and the heel attached to the shoe. The die-bed spindle W has attached to it at one side, 60 between its two bearings j^2 and j^3 , a block, h^2 , which has pivoted upon it at 48 a hook, g^3 , 65 acted upon by a spring, l^4 , and adapted at each descent of the said spindle to engage the bearing j^2 and prevent the die-bed spindle 70 from jumping. To release this hook I have provided a lever, l^5 , pivoted at h^2 , and acted upon by a foot-lever or treadle, J, through a link, m^2 .

In another application filed by me May 3, 1884, Serial No. 135,241, I have shown a top-lift plate operated in one direction by hand and in the other direction by a spring. 75

I am aware that a so-called "spanker" or "holder" has been supplied with a top lift, 80 and that the said holder in its rotation has placed the top lift above the tread of the heel, the plate of the said spanker or holder serving to resist the thrust of the ends of the nails left protruding beyond the tread of the heel. 85

Prior to my invention I am not aware that a top-lift plate has ever been automatically swung on its pivot above the nail-box, either to cover or to uncover the nail-box. 90

I claim—

1. In a heel-ing-machine, the combination, with the nail-box and a top-lift plate, of means, substantially as described, to automatically move the said plate into position above the nail-box to cover the same preparatory to applying the top lift, substantially as described. 95
2. In a heel-ing-machine, the top-lift plate and the nail-box, combined with a connecting-rod to automatically operate the said top-lift plate to move it into or out of position with relation to the nail-box, substantially as described. 100
3. In a heel-ing-machine, the nail-box, combined with a top-lift carrier, substantially as described, to engage a top lift and place it in position between the top-lift plate and the end of the heel, to operate substantially as described. 105
4. In a heel-ing-machine, the nail-box, the top-lift plate, and top-lift carrier, combined with means to actuate the top-lift carrier to take a top lift and move it into position between the top-lift plate and heel of the boot or shoe, substantially as described. 110
5. The nail-box and the top-lift carrier, having jaws to grasp and hold the top lift, combined with the slide-bar and means to reciprocate it and the carrier forward and backward with relation to the nail-box, as and for the purpose described. 115
6. A plate or table, S, and the top-lift carrier and nail-box, combined with means to move the said carrier to present a top lift in position below the heel of the boot or shoe with which the top lift is to be attached, and thereafter withdraw the said carrier, substantially as described. 120
7. In a heel-nailing machine, the nail-box, the top-lift plate, and means to automatically operate the said top-lift plate, combined with the top-lift carrier and with means to automatically operate it, substantially as described. 130
8. The combination, with the die-bed spindle W, of an attached hook to engage a fixed

part of the frame at the completion of each descent of the said working-spindle, substantially as described.

9. The combination, with the die-bed spindle W and the attached hook to engage a part of the frame-work at the descent of and to lock the said spindle down, of a treadle and connected devices to release the said hook when the spindle is again to be lifted, substantially as described.

In testimony that I claim the foregoing as my own I have affixed my signature in presence of two witnesses.

EDWARD B. ALLEN.
